Inventor:

Joseph Selinger Balzer

UNITED STATES PATENT OFFICE.

JOSEPH SELINGER-BALZER, OF OBERSTEINMAUR, SWITZERLAND.

CLIMBING-IRON.

1,395,234.

Specification of Letters Patent. Patented Oct. 25, 1921.

Application filed December 3, 1920. Serial No. 428,174.

To all whom it may concern:

Be it known that I, JOSEPH SELINGER-BALZER, a citizen of Switzerland, residing at Obersteinmaur, Switzerland, have invented certain new and useful Improvements in Climbing-Irons, of which the following is a specification.

This invention relates to a climbing-iron for climbers, laborers mowing grass in the mountain-ridges, and other persons. The new climbing-iron consists essentially of a bow for putting on a foot, and a lever pivotally mounted on a horizontal axle fastened to said bow, the lever having pivotally connected a spur with each of its ends.

The new climbing iron is represented in the accompanying drawings, in which Figure 1 shows the climbing-iron partly in front-view and partly in section, Fig. 2 is an upper view of the same, partly in section, and Fig. 3 is a side-view.

a is the central part of a bow serving as foot-rest and being provided with walls *e*. In the latter is fastened an axle *f* forming a pivot for the lever *g*. Each of the ends of the latter possesses a trunnion *i* with which a

double-pointed spur *h* is connected. Each spur has a stud *k* by means of which the said spurs are guided in grooves *m* of the arms *h*. To each arm *b* is fastened a flat spring *n* pressing against the spur for securing the latter in its position. Fig. 1 shows that the part *a* serving as a footrest has always a horizontal position or nearly so, even if the soil is strongly inclined. Hereby the user of the climbing iron is allowed to stand securely.

I claim as my invention:

A climbing-iron comprising a bowed member having grooves at each end and adapted to serve as a foot-rest, a lever having a horizontal axis centrally of its ends mounted on said bowed member, and a pivotally mounted spur at each end of the lever and arranged to be guided in the grooves of said bowed member.

In testimony whereof I have affixed my signature in presence of two witnesses.

JOSEPH SELINGER BALZER.
